BRANNER ROLL

Howard C. Rodgers, Birmingham, Ala.

Application October 7, 1939, Serial No. 298,475

3 Claims. (Cl. 51—190)

The present invention relates to branners such as used for polishing and cleaning tinned sheets. In such branners, the sheets are customarily passed between two sets of rolls immersed in fine middlings or bran, and wherein alternate rolls of an upper set revolve at speeds varying from the speeds of opposed rolls of a lower set, thus exerting a wiping or polishing action on the sheets through the medium of the middlings or bran.

Heretofore rolls used in branners have been made of cloth discs pressed on a steel shaft and turned down to the required diameter. Such cloth rolls in practice are not wholly satisfactory because of their tendency to wear out of round and to become loose on the shaft. They also have a relatively short life. An object of the present invention is to provide an improved type of branner roll which will have an increased life and will maintain its roundness or cylindrical shape for a long interval and will thus minimize the maintenance expense of a branner and effect savings over conventional types by lessening the periods for which the branner is out of production due to shut-downs necessitated by changing rolls or replacing eccentric cloth rolls heretofore used. The foregoing and further features of the invention will be fully apparent from the following detailed disclosure, the accompanying drawings, and the appended claims.

In the drawings, Figure 1 is a somewhat diagrammatic plan view of a branner equipped with improved rolls of the present invention.

Figure 2 is a side elevation of Figure 1.

Figure 3 is an enlarged view partly in elevation and partly in longitudinal section, showing constructional details of the improved branner roll.

Figure 4 is a cross section on line IV—IV of Figure 3.

Figure 5 is a greatly enlarged longitudinal sectional view of a sleeve portion of the improved branner roll illustrating the conical depressions thereof.

Figure 6 is a development of the surface of the sleeve of the roll illustrating the layout of the depressions therein.

Referring in detail to the drawings, Figures 1 and 2 show somewhat conventionally a branner having an upper receptacle 10 and a lower receptacle 12, each containing a supply of bran or middlings indicated at B and B—1. A plurality of upper rolls 14 are supported in suitable bearings and arranged to be rotated by any conventional driving mechanism. Similar rolls 14a are arranged in opposed relation to the rolls 14,

and these are also supported in suitable bearings and driven by any conventional driving means.

The particular feature of the present invention relates to the construction and arrangement of the branner rolls 14 and 14a, best shown in Figures 3 to 5, inclusive.

Each of the improved branner rolls is characterized by the provision of a multiplicity of cavities 16 which are depressed below the cylindrical surface 18 of each roll. As shown in an enlarged scale in Figure 5, each cavity 16 corresponds to the surface of an obtuse cone. While not limited thereto, I have found that highly satisfactory results are secured by forming these conical cavities of a depth indicated at d in Figure 4, equal to about $\frac{1}{16}$ inch, and a diameter D of approximately $\frac{1}{16}$ inch. The included angle between the faces of the obtuse cone, as indicated by the arc A, is approximately 114 degrees. In practice, I find it convenient to form the conical cavities 16 in a sleeve-like member 20, which may conveniently be formed of a length of extra-heavy metal pipe, the same being provided at its ends 22—22 with trunnion extensions 24—24 turned down to engage suitable bearings. One trunnion is extended as indicated at 26 and provided with a key 28 for securing thereto a suitable drive gear or pulley. The pipe-like sleeve is secured to the arbors in any suitable manner; for example, by welded joints such as indicated at 30—30. As will be apparent from the developed view, Figure 6, the conical cavities are arranged in staggered relationship. This developed view in its greatest dimension represents the circumference of a roll of 5.493 inches diameter. This provides for 18 rows of holes spaced on centers .9591 inch. The lead in one turn for any series of holes, as indicated by the center line M—M, is 6 inches. Thus it will be seen that as the roll turns, the individual masses of bran picked up by the several conical cavities will be progressed in a helical fashion. Thus there will be a combined rotating and end-wise action exerted by the bran on the sheet. As this action is taking place simultaneously among many parts of the roll, it is apparent that the entire surface of the sheet passed in contact with such roll will be effectively cleansed and polished through the action of the middlings or bran picked up. It is believed advantageous to have the cavities of cone-like form because the tapering forms of the walls bring about a slight compression of the bran particles trapped in the cavity. Thus a yielding pressure of pocketed masses of bran at a multiplicity of points along each roll is secured.

While I have described quite specifically detailed features of the particular embodiment of the invention herein illustrated, it is to be understood that various modifications may be made by those skilled in the art without departure from the invention described in the appended claims.

I claim:

1. Apparatus of the character described, including a receptacle containing a polishing medium, a roll arranged to have a portion thereof immersed in such medium, said roll being characterized by the provision of a substantially cylindrical surface with a multiplicity of exposed cavities adapted to pick up the medium and apply it with a rubbing action to the surface of a sheet to be cleaned or polished.

2. A branner of the character described, including a receptacle containing a polishing medium, a roll of rigid material arranged to

have a portion thereof immersed in such medium, said roll being characterized by the provision of a substantially cylindrical surface provided with a multiplicity of conical cavities adapted to pick up the spaced bodies of the medium and apply them with a yielding rubbing action to the surface of the sheet to be cleaned or polished.

3. A branner of the character described, including a receptacle containing a polishing medium, a roll of rigid material arranged to have a portion thereof immersed in such medium, said roll being characterized by the provision of a substantially cylindrical surface provided with a multiplicity of obtuse conical cavities, each cavity effective to pick up a small quantity of bran and to yieldingly press a respective body of bran against the surface of a sheet to be cleaned or polished.

HOWARD C. RODGERS.
